UNITED STATES PATENT OFFICE.

CLAUDE H. COOK, HARRY JAY LEWIS, AND CHARLES E. LEWIS, OF CLEVELAND, OHIO.

ATTACHMENT FOR ELECTRIC STOVES.

Application filed June 30, 1922. Serial No. 572,059.

To all whom it may concern:

Be it known that we, CLAUDE H. COOK, HARRY JAY LEWIS, and CHARLES E. LEWIS, citizens of the United States, residing at 5 Cleveland, in the county of Cuyahoga and State of Ohio, have invented certain new and useful Improvements in Attachments for Electric Stoves, of which the following is a specification.

10 This invention relates to improvements in electric stoves and attachments therefor and more especially to that class of stoves which are adapted for use upon the dining room table and other such places.

15 The objects of this invention are to provide means for anchoring the lead wires of an electric stove or the like to the frame thereof so as to remove the strain from the points of connection of the wires to the binding posts; furthermore, to provide a clip which can be stamped out of sheet metal and which can be clamped about the wires and readily and firmly attached to the frame of the stove.

20 25 Other objects of the invention will be apparent from the following description and claims when considered together with the accompanying drawings.

Fig. 1 is an end elevation of an electric 30 stove with our improved attachment applied thereto; Fig. 2 is a bottom plan view of the stove with our attachment applied thereto; Fig. 3 is a bottom plan view of the end portion of the deflector plate to which the attachment is secured; Fig. 4 is a view taken on line 4—4, Fig. 1; and Fig. 5 is a detail view taken on line 5—5, Fig. 3.

The attachment here set forth is adapted for use especially in connection with that 40 type of stove here illustrated in part and illustrated more fully in our co-pending application, Serial No. 489,828, filed August 4, 1921.

The legs 1 support the asbestos pad 2 on 45 the top surface of which is arranged a heating coil whose ends have electric connection through the binding posts 3 with the terminal portions 4 of the wire connections 5. The terminal portions of the wiring are 50 covered with asbestos or other suitable covering and in this particular case are led through the recess 6 provided in the edge of the deflector plate 7. Plate 7 is provided with integral tongues 8 at its corner portions 55 for detachable locking engagement

with the ears 9 formed on the legs 1. The deflector plate 7 has a depending flange 10 on each side thereof.

The body portion 12 of our improved attachment extends vertically along the flange 60 10 at the recess 6 so as to virtually constitute an aperture through which the terminal portions extend. The edge of recess 6 is flanged so as not to cut the wiring. The upper portion of the attachment is bent inwardly, as 65 indicated at 13, so as to form a flange between which and the plate 7 extend the terminal portions of the wiring. There are also provided ears 14 extending inwardly from the body portion 12 and contacting 70 the under surface of the deflector plate 7. The ears 14 are so bent as to form tapering sides as indicated at 12^a which merge in the lower outwardly extending conduit portion 12^b. The integrally formed tongues 15 are 75 adapted to extend upwardly through the openings 16 provided in the deflector plate 7 and to be bent inwardly against the upper face of the plate 7 so as to firmly secure the attachment in position. 80

It will be noted that at the points where the ears 14 join the main body portion 12 of the attachment, there are formed depressions or recesses 17 into which depends the flange 10 of the deflector plate 7, thereby 85 further bracing the attachment in position. The conduit portion 12^b is provided with the integral extensions 18 which are adapted to be clamped in substantially cylindrical form about the terminal portions 4 while the flanged openings 19 formed in the depending end portion 20 receive the wires 5. 90

In applying this attachment, the wires 5 are first led through the openings 19, the asbestos or other similar covering is applied to the terminal portions, about which the extensions 18 are then clamped, the terminal portions are then connected to the binding posts and the attachment finally secured to the deflector plate. 100

Thus it will be seen that with this particular attachment the strain upon the end portions of the lead wires is entirely removed from the point of connection at the binding posts. 105

What we claim is:

1. In an electric stove, the combination of a frame, a heating element, electric wiring connected to said heating element, and single unitary means for securing said elec- 110

tric wiring to said frame so as to relieve the strain at the point of connection of the wiring to said heating element.

2. In an electric stove, the combination of a frame, a heating element, electric wiring connected to said heating element, and a one-piece anchoring member attached to said wiring and being firmly mounted upon said frame, thereby relieving the strain at the 10 point of connection of the wiring to said heating element.

3. In an electric stove, the combination of a frame, a heating element, electric wiring connected to said heating element, said frame including a member extending beneath said heating element and substantially within the boundaries of said frame, and means for anchoring said electric wiring to said member so as to relieve the strain at the 20 point of connection of the wiring to said heating element.

4. In an electric stove, the combination of a frame, a heating element, electric wiring connected to the underside of said heating element, said frame including a member extending beneath said heating element and spaced therefrom, and means for anchoring said wiring to said member, the terminal portions of said wiring extending through 30 the space between said heating element and said member.

5. In an electric stove, the combination of a frame, a heating element, electric wiring connected to the underside of said heating element, said frame including a member extending beneath said heating element and spaced therefrom, means for anchoring said wiring to said member, the terminal por- 35

tions of said wiring extending through the space between said heating element and said member, and means for guarding the said terminal portions of the wiring.

6. In an electric stove, a clip consisting of a body portion having means for attachment to the frame of a stove, and having also portions adapted to clamp the wires of an electric connection.

7. In an electric stove, a sheet metal clip having a body portion with integral tongues for attachment to the frame of a stove, and having also integral portions adapted to clamp the wires of an electric connection.

8. In an electric stove, a sheet metal clip having a body portion with integral tongues for attachment to the frame of a stove, having also integral portions adapted to clamp the wires of an electric connection, and a flange adapted to serve as a guard for the terminal portions of the electric wires.

9. In an electric stove, the combination of a frame including legs and a recessed member extending between said legs, a heating element on said frame and spaced above said recessed member, electric wiring extending through said recess and having connection with said heating element, anchoring means secured to said member and extending along said member so as to enclose the wiring in said recess and having portions through which said wiring extends and to which said wiring is firmly secured.

In testimony whereof we hereby affix our signatures.

CLAUDE H. COOK.
HARRY JAY LEWIS.
CHARLES E. LEWIS.
